PLOWSHARE

Fred Warholoski, Columbus, Nebr.

Application December 11, 1946, Serial No. 715,501

3 Claims. (Cl. 97—125)

1

This invention relates to plowshares or plowlays.

Many plowshares associated with tractor plows do not enter the ground quickly nor readily when first released and are inclined, after a short period of use, to spring or pull out of the ground.

An important object of the invention is to provide a plowshare which, when released to enter the ground will so do at once.

Another important object is to provide a plowshare which will not spring nor pull out of the ground while in use.

Plowshares are, in the main, relatively heavy and one of the important objects of this invention is to provide a particularly light weight, thin, but very sturdy plowshare, which may be attached to conventional plow bodies without altering the latter.

Still another important object is to provide a plowshare, so constructed that it will not require frequent resharpening. In fact, it has been discovered that this plowshare will plow until it is substantially worn out, without resharpening. All that is required is hard refacing of the point after an average 150 to 200 acres of plowing.

Other objects and advantages of the invention will be apparent during the course of the following detailed description of the invention, taken in connection with the accompanying drawing, forming a part of this specification, and in which drawing:

Fig. 1 is a perspective view of one face of the novel plowshare.

Fig. 2 is a perspective view of a fragment of the other face thereof.

Fig. 3 is a section upon substantially the line 3—3 of Fig. 2.

Fig. 4 is a perspective view, similar to Fig. 1, but on a reduced scale, of the new plowshare, and those portions of a plow body to which it is constructed and arranged to be attached.

In the drawing, wherein for the purpose of illustration is shown a preferred form of the invention and wherein similar reference characters designate corresponding parts throughout the several views, the novel plowshare is designated as A and a plow body, to which it may be attached, as B.

The new plowshare A includes a main body portion 10 and a knife portion 11.

As may be seen, particularly in Figs. 1 and 2, the main body portion 10, has opposite faces 12 and 13, a knife portion abutting edge 14 which is preferably substantially straight, a longer rear 55

edge 15 which may be substantially straight and forms an obtuse angle with the edge 14, a short upper edge 16 which may also be substantially straight and a forward or front edge 17 which may be substantially straight as at 18, for a portion of its length adjacent its juncture with the edge 16 but is concave, as at 19, from the lower end of the straight edge portion 18 to adjacent the juncture of the edge 17 with the edge 14, but the extreme lower portion of the edge 17 changes from concave to convex, as at 20, from the edge portion 19, to the juncture of edges 17 and 14. While the edges described are more or less like the edges of some conventional plowshares, they have been described so as to better associate with them novel features of the new plowshare. The main body portion 10 is provided with the usual stud 21 and bolt and nut assembly 22 projecting from the face 12.

It is preferred to construct the body portion 10 of vanadium spring steel and the convex edge portion 20 is preferably hard-faced with a suitable facing metal.

Associated with the body portion 10 is the knife portion 11. As may be seen in Figs. 1, 2 and 3, this portion 11 extends to both sides of the planes of the faces 12 and 13 of the portion 10, and is disposed along the edge 14, with the portions 10 and 11 forming, in cross section, somewhat of a T, as in Fig. 3. From the end of the convex edge portion 20 the edge 25 of the knife portion extends outwardly to meet a blunt edge 26 which extends to the edge 15 of the portion 10. The face 12 forms, with the plane of this knife section 27, an acute angle (about 85°). From the same end of the convex edge portion 20 the knife edge 28 extends in an arc to join the edge 14 intermediate its length. This section 29 of the knife portion forms, with the face 13, an obtuse angle (about 95°). The edge 23 is sharpened and properly hard faced with a suitable facing metal. Extending from the section 27 is a conventional stud 30 and the edge 26 is indented by a short, arcuate slot 31.

Again referring to the body portion 10, it will be seen in Fig. 1 that there are two ribs 35 and 36 extending from, preferably, the knife portion 11 over the face 12 of the body portion. The rib 35 extends over the face 12 adjacent the edge 15 to the edge 16 and the rib 36 extends over the face 12 intermediate the edges 15 and 17 converging toward the rib 35 and meets it, at the edge 16 in a curve. Extending across the face 12 from rib to rib are cross ribs 37, 38 and 39.

These several ribs are not only for the purpose of strengthening the body portion 10 (which latter may be much thinner than conventional plowlays) but they also strengthen the stud 21 and bolt 22. Because of the thinness of the portion 10, the ribs provide the additional thickness necessary to enable the new plowlay to be properly coupled so as to be flush with the moldboard of the plow body B.

From Fig. 1 it will be seen that the knife portion 11 is provided with a pair of substantially parallel ribs 40, extending from the edge 26 to either side of the slot 31 toward, but falling short of the stud 30. These ribs 40 are also provided for the purpose of strengthening the knife section 27 and, because of the thinness of this section, to build up the thickness in order to properly associate the knife portion 11 with the bracket portion of the plow body B, next to be described.

The plow body B, which is of conventional construction, and is shown in Fig. 4 includes a moldboard 45, frog 46, having a V-slot 47 and brace assembly 48 extending from the moldboard 45 to the slot 47. A U-shaped slot 49 is in the end portion of a casting 50 secured to the moldboard 45 and frog 46, with this casting 50 having a U-shaped projection 51 inwardly of the slot 49, which slot 49 and projection 51 are carried by a bracket portion 52 which bracket portion 52 forms the end section of the casting 50. The end of the brace assembly 48 within the slot 47 has a slot 53. A casting 54, carried by the casting 50 and extending along the moldboard 45, has a U-shaped slot at its free end.

In securing the plowshare A to the plow body B, the body portion 10 slides over the outer face of the bracket portion 52 until the projection 51 fits snugly into the slot 31 and the stud 30 extends into the U-slot 49. At the same time the stud 21 will engage the walls of the V-slot 47. The brace 48 is manipulated so that the slot 53 extends around the stud 21. In addition, the bolt shank of the bolt and nut assembly 22 will extend into the U-slot 55 of the casting 54. The plowshare is then drawn into rigid engagement with the plowshare body by tightening the nut of the bolt and nut assembly 22 and by means of the brace assembly 48.

By the use of the ribs 35 to 40, a plowshare may be built to weigh but 7½ pounds, for example, as compared with the usual plowshare of about 12½ pounds and, because of the strong construction (vanadium steel, is preferred, with the cutting edges hard faced), the new plowshare will cut as much or more than conventional, heavier plowshares, and will not require resharpening.

As a result, although my plowshare A has the portions 10 and 11 much thinner [for example, the thickest portion of body portion 10 need not be over $\frac{1}{16}$ inch and the thickest portion of the knife portion (along the edge 25) is not over $\frac{1}{4}$ inch, than the body and knife portions of conventional plowshares] the ribs 35 to 38 inclusive and ribs 40, permit the novel plowshare A to be rigidly coupled to conventional plow bodies, such as B, and the several ribs provide reinforcing for the plowshare body and knife portions.

Various changes may be made to the form of the invention herein illustrated and described without departing from the spirit of the invention or scope of the claims.

What is claimed is:

1. In a plowshare for association with a plow body having a plowshare body portion-contacting face and a plowshare knife portion-contacting face, said plowshare comprising a body portion and a knife portion, said knife portion extending outwardly of the planes of opposite faces of said body portion, said body portion having a plurality of ribs projecting from one face thereof and said knife portion having a pair of ribs projecting from one face thereof disposed to one side of said planes, the ribs of said body portion being constructed and arranged to extend over and in face contact with said body portion-contacting face and said pair of ribs being constructed and arranged to extend over and in face contact with said knife portion contacting face.

2. In a plowshare for association with a plow body having a plowshare body portion-contacting face and a plowshare knife portion-contacting face, said plowshare comprising a thin body portion and a thin knife portion, said knife portion extending outwardly of the planes of opposite faces of said body portion, said body portion having a plurality of ribs projecting from one face thereof and said knife portion having a pair of ribs projecting from one face thereof disposed to one side of said planes, the ribs of said body portion being constructed and arranged to extend over and in face contact with said body portion-contacting face and said pair of ribs being constructed and arranged to extend over and in face contact with said knife portion-contacting face.

3. In a plowshare for association with a plow body having a plowshare knife portion-contacting face, said plowshare comprising a body portion and a knife portion, said knife portion extending outwardly of the planes of opposite faces of said body portion, said knife portion having a pair of ribs projecting from one face thereof disposed to one side of said planes; said pair of ribs being constructed and arranged to extend over and in face contact with said knife portion-contacting face.
